UNITED STATES PATENT OFFICE.

JACOB SOKOLOV AND ERIC F. WIENEKE, OF DETROIT, MICHIGAN, ASSIGNORS TO
DEFIANCE LOCK CORPORATION, OF DETROIT, MICHIGAN, A CORPORATION OF
MICHIGAN.

LOCK FOR AUTOMOBILES.

Application filed May 27, 1921. Serial No. 473,199.

To all whom it may concern:

Be it known that we, JACOB SOKOLOV and ERIC F. WIENEKE, citizens of the United States, and residents of Detroit, county of Wayne, and State of Michigan, have invented certain new and useful Improvements in Locks for Automobiles, of which the following is a specification.

Our invention relates more particularly to a locking device, associated with the planetary gear steering mechanism of a Ford machine, means being provided for disconnecting the steering wheel, so that it may be rotated independently of the steering post, and thereby prevent unauthorized operation of the machine.

The object of our improvement is to accomplish this by means of a slidable clutch member, the position of which may be controlled by a gear member or other suitable device, operated or rotated by the key barrel of the ordinary Yale type of lock.

Another object is to provide a safety locking means for holding the clutch member in engaging or operative position, thereby preventing accidental displacement when the key is in the lock, and the steering wheel is connected for turning the steering post.

Another object is to provide a hardened steel disc covering the end of the key bow, so as to effectually protect the key barrel from being bored out, and this disc is preferably rotatable independently of the key barrel, thereby making it impossible for anyone to exert pressure in the key barrel by the insertion of a tool or device into the exposed key slot.

Another object is to thoroughly protect the lock and associated parts by making the housings of hardened steel forgings, so as to be capable of resisting a cold chisel, hack saw or other implement, that may be used in attempting to obtain access to the locking mechanism.

The cover cap part of the housing is preferably secured to the gear box part by a locking screw, which is so located as to be inaccessible, except when the clutch member is in operative position, and the various elements of the locking device and clutch operating members are secured or held in proper positions by pins or screws accessible

only from the inside of the hardened steel cover cap.

In other words, it will be seen that we have devised and constructed a substantially fool-proof and burglar-proof automobile steering wheel locking device and provided the mechanism with every means possible to prevent destruction of the mechanism or the access thereto by unauthorized persons.

One form of our improved automobile steering wheel locking device is shown in the accompanying drawings, in which Fig. 1 represents a vertical cross-section of our improved automobile lock with the clutch member in inoperative position, the section being on the line 1—1 of Fig. 6; Fig. 2 is a similar vertical cross-section with the clutch member in operative or clutching position, the section being on the line 2—2 of Fig. 3; Fig. 3 is a top plan view in horizontal section on the line 3—3 of Fig. 2; Fig. 4 is a horizontal cross-section on the line 4—4 of Fig. 1; Fig. 5 is a side elevation with a portion shown in section on the line 5—5 of Fig. 3; Fig. 6 is another side elevation at right angles to the one shown in Fig. 5, with a portion of the casing in section on the line 6—6 of Fig. 1; Fig. 7 is a sectional view on the line 7—7 of Fig. 3 showing the screw for locking the cover cap to the gear housing; Fig. 8 is a detail sectional view on the line 8—8 of Fig. 3, showing the connection between the key barrel and the gear member; Fig. 9 is a sectional detail view on the line 9—9 of Fig. 3, showing the pin for locking the key tumbler in position and Fig. 10 is a perspective view of the hardened steel key slot protecting disc.

Referring to the drawings, 1 represents the upper end of the steering column, in which the usual steering post 2, is adapted to rotate, for steering the wheels. The upper end of the steering column is provided with a gear box or housing 3, in which the usual Ford planetary gears are mounted. The inner periphery of the gear box at 4 is provided with internal gear teeth meshing with pinions 5, rotatably mounted upon the flanged head or block 6, which is connected to and forms a part of the steering post 2, as is usual in the Ford type of steering mechanism.

In the Ford type of steering mechanism, the planetary pinions 5 mesh with a central pinion 7, which in the present instance is elongated and projects a considerable distance above the upper plane of the pinions 5. The pinion 7 is mounted upon a stub shaft 8, rotatably mounted in the block 6, as indicated in Figs. 1 and 2 of the drawings. Ordinarily the steering wheel is connected directly to the central pinion 7, but in our device, as will be seen in the drawings, the upper small end 9 of the stub shaft, integral with the pinion 7 enters a socket 10, in the lower end of an integral pinion 11 and stub shaft 12, the two pinions being in axial alignment and provided with the same number of teeth. The stub shaft 12 is turned down so that the pinion 11 thereon forms a shoulder against which we 10 preferably mount a flange collar 13, against which the hub 14 of the steering wheel 15 may be clamped by the nut 16, as indicated in Fig. 1 of the drawings. The flanged collar 13 passes through a hole in the upper 15 end of the hardened steel cover casing 17, and the flange of the collar holds the steering wheel and pinion for rotation in fixed relation to the pinion 7, which as previously stated is in mesh with the planetary pinions 15.

We preferably mount upon the pinion 11, a clutch member 18, which may be provided with internal gear teeth, corresponding with and adapted to slide on the gear teeth of the pinions 11 and 7, whereby the two pinions may be clutched together to rotate in unison when the clutch member 18 is in the position shown in Fig. 2 of the drawings, and disconnected so that the upper pinion, in connection with the steering wheel, may be rotated independently of the pinion 7, when the clutch member 18 is in the position shown in Fig. 1 of the drawings. As hereinbefore stated, the housing 17 is preferably 40 made of a steel forging and hardened, so as to make it impossible for it to be destroyed or broken into by ordinary tools or appliances.

The casing 17 is preferably provided 50 with a lateral extension 19, as indicated more particularly in Figs. 1 and 3 of the drawings, which is bored out at 20, the axis of the bore extending at right angles to the axis of the steering column. At one end of 55 the housing extension 19, the bore 20 is closed except for the hole 21 through the casing, in which we preferably locate a flanged slotted disc 22, shown in perspective in Fig. 10 of the drawings. This disc is 60 preferably made of special hardened steel, so as to effectively protect the key slot and key barrel against destruction by drilling or otherwise, and prevent tampering with the lock. The flanged disc 22, is slotted at 65 22^a for the key and is freely and independ-

ently rotatable in the hole 21, and the flange 23 thereof is adapted to fit over the boss-like projecting key end of the key barrel 24, as indicated in Fig. 6 of the drawings, the key 25 being here represented as in the 70 key barrel.

Within the cylindrical bore 20 of the extension 19, and adjacent the partially closed end thereof, we preferably mount the usual tumbler barrel or member 26, through which 75 the key barrel or bow 24 passes, the tumblers 27 being spring pressed in the usual well-known manner for Yale locks, as indicated in Figs. 6 and 9 of the drawings. The key tumbler member 26 is preferably 80 of the usual well-known Yale construction, although any other suitable device may be used, and may be secured in place by a concealed pin 28, inserted from the inside of the cover cap of housing 17, as indicated in 85 Fig. 9 of the drawings, thereby making it impossible for an unauthorized person to obtain access to or remove the key tumbler member.

In the cylindrical bore 20, we also mount 90 a substantially cylindrical block or gear member 29, which, near one end at 30, is provided with gear or pinion teeth, adapted to mesh with gear teeth 31, formed on the clutch member 18, by annular grooves thereon, so that the clutch member 18 may be freely rotated while remaining in mesh with the gear teeth 30, as indicated in Figs. 1 and 2 of the drawings. The gear member 29 is rotatably mounted in the cylindrical bore 20, and is preferably provided with a slot or groove 32, indicated in Figs. 1, 2 and 3 of the drawings, into which the inner end of a screw 33 projects for locating and holding the gear member 29 in fixed relation in the bore and to the clutch member 18, while, at the same time, permitting rotation of the gear member 29 for shifting the clutch member 18, as previously described. The screw 33, as will be seen in 100 Figs. 1 and 2 of the drawings, is preferably inserted from the inside of the cover cap 17 of the housing so that the screw is inaccessible from the outside and cannot be tampered with by unauthorized persons. 105

The cover cap 17 is preferably secured to the gear box portion of the housing by screw threads at 34, as indicated in Figs. 1 and 2 of the drawings, and in order to prevent unauthorized removal of the cover 110 cap 17 by unscrewing the same from the gear box 3, we preferably provide a locking screw 35, as indicated in Fig. 7 of the drawings; the screw 35 entering a hole in the flange 36 of the cover cap 17, the hole being 115 a blind hole drilled downward from the top of the cylindrical bore extension 19, as indicated at 37, in Fig. 7 of the drawings. It will be seen that the gear member 29 is also provided with a hole 38, which is off center 120

125 22^a for the key and is off center 130

and adapted to coincide or line up with the hole 37 and the screw 35, when the gear member 29 is in the position indicated in Figs. 2, 3 and 7, which is the position in which the clutch member 18 is in engagement with the steering post pinion 7 and the key 25 is in the lock and turned counter-clock-wise, as viewed in Figs. 1 and 2 of the drawings. It will thus be seen that the screw 35 will be inaccessible from the outside of the casing or housing, when the clutch member 18 is free to rotate independently of the steering post, or in other words, when the steering wheel is disconnected and inoperative for steering purpose.

The gear member 29 is adapted to be rotated in the bore 20, by means of the key barrel 24, which, at its inner end adjacent the member 29, is provided with a slot at 39, as indicated in Fig. 8 of the drawings, which receives a transversely extending pin 40, extending across an annular or collar-like member 41, provided with a radially extending tooth or finger 42, as indicated in Fig. 8 of the drawings. The finger or tooth 42 is adapted to extend into a slot 43, formed by slotting a projecting lug 44 on the end of the gear member 29, as indicated in Figs. 3, 6 and 8 of the drawings. By this arrangement it will be seen that, while the key barrel 24 and gear member 29 are rotatable about different parallel axes, they will be rotated in unison, by means of the tooth 42 and slot 43. The gear member 29 is required to rotate only about one-third of a complete rotation, the amount of rotation being indicated by a comparison of Figs. 1 and 2 of the drawings.

In order to provide a safety means for preventing accidental release of the steering wheel by a movement of the clutch member 18 and gear member 29, we preferably provide the latter with a safety locking pin 45, mounted in a blind hole 46, and spring pressed radially of the gear member 29 by a spring 47, as indicated in Fig. 5 of the drawings. When the gear member 29 is rotated to the position shown in Figs. 3 and 5 of the drawings, the safety locking pin 45 is adapted to enter a hole 48, in the cylindrical wall of the casing extension 19, and thereby lock the gear member 29, and hence the clutch member 18, against accidental displacement from the position shown in Figs. 2 and 3 of the drawings. In order to provide means for releasing the safety locking pin 45, the housing cover cap 17 may be preferably provided with another lateral extension 49, counter-bored at right angles to the bore 20, which contains the gear member 29. The housing extension 49 is counter-bored at 50, substantially larger than and in axial alignment with the hole 48, which is adapted to cooperate with the locking pin 45,

when the gear member 29 is in the position shown in Fig. 5 of the drawings.

In the counter-bore 50, there is preferably mounted a spring pressed key member 51, turned down at 52, to provide an annular groove, through which a retaining pin 53 passes, as indicated in Figs. 3 and 5 of the drawings, to limit the movement of the key member 51. The pin 53 is preferably inserted from the underside of the casing 17, as indicated in Fig. 4 of the drawings. The key member 51 may be held outward against the pin 53 by a spring 54, pressing against a shoulder of the key member at 53 and against the bottom of the counter bore 50, the spring surrounding a stem 56, which is of the same diameter as the locking pin 45 and adapted to limit the outward movement of the latter, as shown in Fig. 5 of the drawings. From this, it will be seen that by pressing on the key 51, the stem 56 thereof may be thrust inward against the pressure of the spring 54 (and spring 47) and release the locking pin 45 from the hole 48, so that the key 25, when turned counter-clock-wise in Fig. 5 may rotate the gear member 29 in the reverse direction to move the clutch member 18 upward and free the pinion 7, thereby permitting independent rotation of the steering wheel.

The gear member 29, as previously described, is held in proper relation to the other cooperating parts of the mechanism by the screw 33 in the slot 32, and the cylindrical bore 20, in which the gear member 29 is rotatably mounted is preferably closed, at the left end, as indicated in Fig. 6 of the drawings, by a disc 57 of a suitably hardened metal the disc being inserted in a counter bore 58, so that excessive pressure on the disc 57 will not affect the movement of the gear member 29 or other parts in the bore 20.

It will thus be seen that we have provided a locking mechanism for the steering wheel of the automobile, made of such materials and in such a way that it cannot be tampered with when the clutch member 18 has been disconnected and in position for free rotation of the steering wheel independently of the steering post, at which time the Yale key 25 should be removed from the lock.

From the description which has already been given it will be understood that the operation of our device is comparatively simple, the key 25 being inserted into the key bow or barrel 24, through the slotted hardened disc 22 and turned clock-wise (counter-clock-wise as seen in Figs. 1 and 2) the gear member 29 will be rotated by means of the connecting member 41-42 to move the clutch member 18 downward from the position indicated in Fig. 1 of the drawings, to the position indicated in Fig. 130

2 of the drawings, thereby permitting steering by the steering wheel in the usual way. When the gear member 29 is turned to the position shown in Figs. 2 and 5 of the drawings, the locking pin 45 is adapted to enter the hole 48 and lock the gear member 29, and hence the key barrel 24 in the position indicated in Fig. 2 of the drawings, with the steering wheel in operative connection for ordinary steering of the wheels, the locking pin 45 being effective for preventing accidental displacement of the clutch 18 or locking member 29. When it is desired to free the steering wheel for protection purposes, the safety key member 51 (see Fig. 5) is pushed inward, the key stem 56 thereof being adapted to unlock the gear member 29 by pushing the locking pin 45 inward, and then the Yale key 25 may be 15 rotated in the opposite direction to move the gear member 29, together with the clutch member 18, back to the position indicated in Fig. 1 of the drawings; thereby freeing the steering wheel, so that any rotation thereof will be incapable of effecting steering of the wheels. When in this position, Yale key 25 should be withdrawn. The key barrel and gear member 29 will be held in that position, shown in Fig. 1, 20 by the key tumblers 27 operating in the usual manner and no unauthorized person can obtain access to the vital parts of the locking mechanism, for, as previously pointed out, the housing parts are all of 25 specially hardened steel and none of the operating parts of the mechanism are accessible from the outside of the casing, and the cover cap cannot be removed because of the locking screw 35.

40 We have shown and described one form and adaptation of our improved locking mechanism, but obviously we do not wish to be limited to the specific construction shown for various modifications in the 45 specific details may be made without departing from the spirit and scope of the invention.

We claim:

1. A steering wheel locking and releasing 50 device, comprising a stub shaft, to which the steering wheel is secured, a second stub shaft carrying a pinion and connected by intermediate pinions with the steering post, said stub shafts being in axial alignment, 55 a clutch member slidably mounted thereon for uniting the two stub shafts for rotation in unison, said clutch member being movable to a position for disconnecting the second stub shaft, whereby the first stub shaft 60 and the steering wheel may be rotated independently of the steering post, annular gear teeth on said clutch member and a rotatable gear member in fixed relation thereto and cooperating with said annular teeth 65 for operating said clutch member.

2. A steering wheel locking and releasing device, comprising a gear box mounted on the end of the steering column, a cover cap screw threaded on to said gear box, a clutch member slidably mounted within said cover cap and provided with annularly arranged gear teeth, thereby permitting the clutch member to be rotated with the steering wheel, a transversely extending gear member mounted in said cover cap and adapted 70 to cooperate with the gear teeth of said clutch member for moving the same, a screw for locking said cover cap to said gear box, and means whereby said screw is accessible through the cover cap only when said gear 75 member is in a predetermined position.

3. A steering wheel locking and releasing device, comprising a gear box secured to the upper end of the steering column, a cover cap adapted to be secured thereto by 80 a screw threaded flange, a clutch member within and movable longitudinally of the axis of said cover cap and provided with annular gear teeth, thereby permitting the clutch member to be rotated with the steering 85 wheel, a gear member mounted in a lateral extension of the cover cap, the axis of said gear member extending at right angles to the axis of said clutch, a key barrel 90 for rotating said gear member, a screw in the threaded flange of said cover cap, for locking the cover cap to the gear box in place, and means whereby said screw may be operated only when the key is in the key 95 barrel and the latter, together with said 100 gear member is rotated to a predetermined position.

4. A steering wheel locking and releasing device, comprising a gear box on the upper 105 end of the steering column, a cover cap secured thereto by a screw threaded flange, a stub shaft mounted in the upper end of said cover cap, a flanged bushing mounted on said stub shaft, said stub shaft being provided with pinion teeth against which said 110 flanged bushing is adapted to rest, means for securing a steering wheel to said stub shaft and clamping it against said bushing and a clutch member provided with internal teeth cooperating with the pinion 115 teeth on said stub shaft and mounted for sliding movement thereon.

5. A steering wheel locking and releasing device, comprising a gear box on the upper 120 end of the steering column, a cover cap secured to said gear box, a pair of stub shafts in axial alignment with the steering post, one of said stub shafts extending through said cover cap and to which the steering wheel is secured, a clutch member slidably mounted upon said stub shafts for securing the same together, annular gear teeth on said clutch member, thereby permitting the latter to be rotated with the steering wheel, 125 a gear member rotatable in fixed relation 130

and at right angles to the axis of said stub shafts, said gear member being in constant engagement with the annular teeth of said clutch, means for rotating said gear member and a spring pressed locking pin for locking said gear member in predetermined position with said clutch member in clutching position.

6. A steering wheel locking and releasing device, comprising a gear box mounted on the upper end of the steering column, a cover cap secured to said gear box, a slideable and rotatable clutch member movable axially of said steering column within said cover cap, said clutch member being provided with annular gear teeth, a lateral extension for said cover cap provided with a cylindrical bore the axis of which is at right angles to the axis of said clutch member and the steering column, a gear member mounted in said bore and provided with teeth adapted to cooperate with the annular gear teeth of said clutch member, a key tumbler mounted in said cylindrical bore and connecting means between said key tumbler and the gear member, whereby a key inserted in the key tumbler is adapted to rotate said gear member.

7. A steering wheel locking and releasing device, comprising a gear box on the upper end of the steering column a cover cap secured thereto, said cover cap being provided with a lateral extension bored out at right angles to the axis of the steering post,

a clutch member mounted within said cover cap and adapted for longitudinal movement axially of said steering column, said clutch member being provided with annular gear teeth, thereby permitting it to rotate with the steering wheel, a cylindrical gear member rotatably mounted in said lateral extension bore, said gear member being in constant engagement with the annular gear teeth of said clutch member, means for holding said gear member within the bore in fixed relation thereto, but permitting rotation thereof, said means being accessible only from the inside of said cover cap.

8. A steering wheel locking and releasing device, comprising a gear box on the upper end of the steering column, a cover cap secured thereto, said cover cap being provided with a lateral extension bored out at right angles to the axis of said steering column, a clutch member slidably and rotatably mounted in said cover cap and provided with annular gear teeth, a gear member cooperating with said annular gear teeth and in constant mesh therewith, rotatably mounted in said bore, means for holding said gear member in fixed relation within said bore but permitting rotation thereof, and means for closing the end of said bore to prevent access to said gear member.

JACOB SOKOLOV.
ERIC F. WIENEKE.
